UNITED STATES PATENT OFFICE.

JOHN McCAFFREY, OF LAWRENCE, MASSACHUSETTS.

DESIGN FOR A HUB FOR FRICTION-CLUTCHES.

SPECIFICATION forming part of Design No. 34,832, dated July 23, 1901.

Application filed February 25, 1901. Serial No. 48,856. Term of patent 14 years.

To all whom it may concern:

Be it known that I, JOHN McCAFFREY, a citizen of the United States, residing at Lawrence, in the county of Essex and State of Massachusetts, have invented a certain new, useful, and original Design for Hubs of Friction-Clutches and Similar Machines, of which the following is a specification, reference being had therein to the accompanying drawings.

This invention relates to a new and original design for hubs of friction-clutches and similar machines.

Figure 1 represents a side view of a hub for friction-clutches and similar machines, illustrating my new design. Fig. 2 represents a cross-sectional view of the same. Fig. 3 represents a side view opposite to that illustrated in Fig. 1.

The leading feature of my new design for hubs of friction-clutches consists in the design of the hub, as herein shown and described.

As shown in the drawings, the member 5 has at one side the central conical extension 6 with the annular groove 7 and the open perforations 8 in said groove. From the periphery of the member 5 extends the flange 9, forming a circular chamber at this side of the member, of which the extension 10 is centrally disposed, the extensions 6 and 10 being centrally perforated.

What I claim is—

The design for a hub for friction-clutches and similar machines as herein shown and described.

In testimony whereof I affix my signature in presence of two witnesses.

JOHN McCAFFREY.

Witnesses:

W. STANLEY CAMPBELL,
HENRY J. MILLER.
